UNITED STATES PATENT OFFICE

2,324,937

ADJUSTABLE GRINDING WHEEL DRESSER

Henry W. Kropf, Muskegon Heights, Mich., assignor to Brickner-Kropf Machine Company, Muskegon Heights, Mich., a corporation of Michigan

Application May 3, 1943, Serial No. 485,415

4 Claims. (Cl. 125—11)

This invention relates to grinding wheel dressers, and is more particularly directed to a grinding wheel dresser of an adjustable character and as a very desirable and practical improvement upon the structure disclosed in Patent No. 2,137,690 issued November 22, 1938.

As shown in said prior patent a novel and very useful wheel dresser is provided. Such construction however requires for the complete and final dressing of a grinding wheel the initial rough dressing with one dressing diamond and, thereafter, a final dressing and finishing with another. Furthermore for each size or diameter of wheel dressed an adjustment of the table of the grinding machine is required inasmuch as the location of the dressing diamond is at a fixed distance above the base on which it is mounted; or, alternatively, for substantially each diameter or size of wheel treated a dressing tool would need to be supplied.

In the present invention the wheel dresser is of universal use for all diameters of dressing wheels between a maximum and minimum limit of such diameters and also both the rough and finished dressings are done without removal of the tool from the grinding machine which is being taken care of, that is, there is no taking away of the rough dressing diamond and putting in its place the finished dressing diamond with the supporting structure which each of them has as used in previous practice.

An understanding of the invention by means of which these desirable results are accomplished may be had from the following description taken in connection with the accompanying drawing, in which,

Fig. 1 is an elevation of the improved wheel dresser of the invention illustrating its utility in connection with different diameters of grinding wheels.

Fig. 2 is an enlarged elevation of the improved wheel dresser.

Fig. 3 is a plan view thereof with a part broken away and shown in section for better disclosure, and

Fig. 4 is a fragmentary elevation of the lower part of the wheel dresser, the elevation being at right angles to that shown in Fig. 1.

Like reference characters refer to like parts in the different figures of the drawing.

In the use of my invention a guiding templet carrying base 1 has at one edge thereof, the guiding templet 2 mounted thereon by means of a clamp 3, the free edge of the templet being shaped in accordance with the contour of the

grinding wheel to be dressed. Upon the base 1 the wheel dresser of the invention is placed and is movable thereover.

Such wheel dresser includes a base 4 having a flat horizontal under side to bear upon the flat upper side of the base 1 previously described. From the base 4 at opposite sides guiding members 5 and 6 extend, shaped at their ends to engage the templet 2 and being located directly below and in the same vertical plane with the dressing diamonds mounted thereabove and having the same shape and form.

In the present invention a post 7 preferably square in cross section is in fixed connection with the base 4 and extends upwardly therefrom. At one of the sides a corner is cut away leaving a flat surface 8 upon which a suitable indicating scale is made as shown.

On the post 7 a hub or sleeve 9 is mounted for vertical adjustment from opposite sides of which arms 10 extend outwardly which at their outer ends carry the supports 5a and 6a for diamond dressers which are secured at their outer ends, said supports 5a and 6a being located directly over the templet engaging parts 5 and 6 previously described.

A clamping screw 11 is threaded through the hub or sleeve 9 having its axis substantially at right angles to the plane of the surface at 8, and at its inner end is equipped with a bearing member 12 with which it has a swivel connection, the inner surface of said member 12 riding against the flat surface 8 on the post 7. With this construction the hub 9, arms 10 and the diamond dressers may be adjusted and held in any position to which adjusted in the length of the surface 8 on the post 7, as is evident.

The templet base 1 in the use of the invention is placed upon the upper side of the table 13 of the grinder and located so that the templet 2 is directly below the wheel 14 which is to be dressed and is adjusted and placed and held so that the free edge of the templet will govern the dressing of the surface of the grinding wheel at the plane 45 of the horizontal diameter of such wheel. The tool is moved back and forth keeping the bearing end of the guiding member 5 for example against the edge of the templet and as the dressing diamond of the part 5a is in exact vertical alinement therewith the grinding wheel is dressed to conform to the templet conformation.

This step of the grinding may be performed for the first or rough dressing of the wheel for example by the diamond carried by the part 5a, and then by moving the tool around to occupy

a position at 180° from its original position and bringing the guide 6 of the dressing diamond 6a against the templet, the finishing dressing of the wheel is performed.

With a wheel of a different diameter, such as indicated in dotted lines at 15 in Fig. 1, the clamping screw 11 is loosened and the dressing diamonds lowered so as to be in horizontal alinement with the axis of the wheel at 15, the rough and finishing operations being performed as before.

With this invention there is an avoidance of moving the grinding wheel table up and down for dressing and the guiding point on the member 5 and the dressing diamond may be brought closer together than with the previous wheel dresser described in the patent above mentioned, with a greater avoidance of any tendency of the post which carries the dressing diamond to vibrate which, if it occurs, is disadvantageous to accurate grinding wheel dressing.

The invention is defined in the appended claims and is to be considered comprehensive of all forms of structure coming within their scope.

I claim:

1. Apparatus for dressing grinding wheels to a desired contour comprising, a base member, a templet mounted thereon having a predetermined contour at one edge for reproduction on the peripheral face of a grinding wheel, a member having a base resting upon and adapted to be moved over the upper side of the first mentioned base in any direction, a plurality of guiding members extending from said second base each of which is selectively adapted to be brought against the contour edge of said templet, a post extending upwardly from said second base, a member mounted on said post for vertical adjustment thereon, means for securing said member to any position to which adjusted, arms on said member, one for each of the guide members and located directly thereabove, and a wheel dressing implement carried by each of said arms, any of said wheel dressing implements being adapted to be pointed toward and located in the same horizontal plane which the axis of the grinding wheel rotates, said guide ends and the dressing points of said dressing implements thereabove being in vertical alinement, as specified.

2. An apparatus for shaping grinding wheels including a base member adapted to be located

with relation to a guiding templet, the edge of which templet is shaped according to the contour of the grinding wheel which is to be dressed, a plurality of guiding members mounted upon and extending horizontally from said base, a vertical post located centrally of the base, a dressing implement holder mounted for vertical adjustment on said post, means for securing the holder to any position to be adjusted, and a plurality of dressing implements carried thereby, one directly over each guiding member and having the points of said dressing implements in direct vertical alinement with the outer end portions of said guiding implements which are adapted to engage with said templet.

3. A construction containing the elements in combination defined in claim 2, said post being rectangular in cross section and having one corner portion cut away vertically for the major portion of the length of the post to provide a flat surface, and the means for securing the dressing implement holder at any adjusted position on the post comprising, a screw threaded through said implement holder and a shoe with which the inner end of the screw has a rotative connection bearing against said flat surface provided at one corner portion of the post, as specified.

4. In a dressing implement of the character described, a supporting base, a vertical post of rectangular cross section centrally located thereon, one corner portion of said post being cut away to provide a flat vertical surface extending from the upper end of the post to adjacent the bottom thereof, a hub located around the post and vertically adjustable thereon, a screw threaded through said hub opposite said flat surface on the post, a shoe within the hub having a flat side bearing against said flat surface and having a connection with said screw permitting rotation of the screw, two arms on said hub extending in diametrically opposite directions, a dressing implement member carried by each arm and having a dressing implement thereon at its outer end, and corresponding guide members carried on the base one directly below each dressing implement and each having a guiding point, the outer end of which is in direct vertical alinement with the outer end of its corresponding dressing implement.

50
